UNITED STATES PATENT OFFICE

2,243,359

PAPER CUTTER

Orville O. Sheline, Chicago, Ill.

Application January 30, 1939, Serial No. 253,586

9 Claims. (Cl. 242—55.5)

My invention relates to a paper cutter of the type commonly known in the trade as a "gravity cutter." It has particular reference to a paper cutter in which provision is made for locking the paper roll stick in position in the saddles on the standards, and also for holding the paper knife upward out of the path of the roll of paper while being placed in position on the standards.

Another and further object of my invention is the provision of a locking member which is simple in application, which effectively holds the roll stick in position on the standards, and which by its own weight automatically seats in position to hold the roll stick in position while paper is being used from the roll.

Another and further object is the provision of a paper cutter having means thereon which is adapted to hold the roll stick in position on the saddles so that all of the paper from the roll can be used instead of, as is the practice at the present time, not attempting to use the last remaining portion of the paper because of the difficulty of holding the small roll of paper on the paper cutter.

With my improved device the roll stick is held in position on the paper cutter until all the paper is removed from the roll stick and in this manner a substantial saving is effected over the practice now commonly followed in the use of these paper cutters.

Another and further object of the invention is the provision of a locking member mounted on the standards, with a cooperating seat portion formed on the knife whereby the knife can be held out of the path of the roll of paper as it is being placed upon the cutter. It is a difficult task for the operator to hold the knife on these gravity paper cutters out of the path of a roll of paper being placed on the cutter, particularly if the roll of paper is heavy. With my improved device this operation is easily accomplished so that the operator is free to use both hands in placing the paper in position and there is less liability of injury to the operator as a result of the use of this improved device.

Another and further object of my invention is the provision of a latch member placed upon the standard in such position that it normally functions to lock the roll stick in position on the standard, and upon being turned in an upward position during the changing of the roll, automatically holds the knife out of the path of the roll of paper as it is being placed upon the standard. In providing means for locking the roll stick in position in the saddles on the cutter, the

roll is held in fixed position so that there is no possibility of the roll of paper being pulled out of the cutter and falling down on the operator, injuring the operator, as has happened in the past, particularly with respect to rather large rolls of paper mounted on these cutters.

These and other objects of my invention will be more fully and better understood by reference to the accompanying sheet of drawings, and in 10 which—

Figure 1 is an elevational view of a paper cutter embodying my invention;

Figure 2 is a transverse sectional view showing the holding device in position to hold the paper 15 roll in position on the standard; and

Figure 3 is a view partially in elevation and partially in section of my improved device in position to hold the knife out of the path of the paper roll.

20 Referring now specifically to the drawing and in which like reference characters refer to like parts throughout, a pair of standards 10 and 11 are provided having foot portions 12, 12 through which screws 13, 13 may pass in order to secure

25 the cutter on a shelf, counter or the like, in position to hold a roll of paper from which sections can be removed for use in wrapping bundles, packages, and the like. The usual cross member 14 is provided which is fitted upon horizontal

30 portions 15, 15 integrally formed with the standards 10 and 11 at the upper ends thereof. Bolts 16, 16 pass through the member 14 and through the portions 15 so that the standards 10 and 11 are held in upright position and in proper spaced

35 relation with each other to accommodate rolls of paper of predetermined width. Slots 17, 17 are provided in the portions 15, 15 through which the bolts 16 pass, which allows for a slight adjustment of the standards 10 and 11 toward or away

40 from each other to provide for rolls of paper of slightly varying width.

45 A knife 18 of the gravity type is provided, having arms 19, 19 at each side thereof, with openings 20, 20 at the upper sides thereof adapted to fit over studs 21, 21 formed at the sides of the standards 10 and 11 and projecting inwardly

50 therefrom, and upon which the arms 19 of the knife 18 are pivotally mounted. Also integrally formed with the standards 10 and 11 on the inner opposed sides thereof is a pair of saddles 22, 22, open at their upper sides. The roll stick 23 of the paper roll 24 is adapted to rest upon the saddles 22, 22 to support the roll of paper 24 upon the standards 10 and 11.

55 The device described up to the present point is

the common, ordinary paper cutter of the gravity type which is old and well-known in the art.

My invention has to do with an improvement upon the parts heretofore described. It comprises a pair of locking members 25, 25 which are pivotally mounted upon inwardly projecting studs 26, 26 formed on the inner side of the standards 10 and 11 and placed intermediate the tops of the saddles 22, 22 and the studs 21, 21 upon which the arms of the paper knife are mounted, so that when the locking members are placed in vertical position, as shown in Figure 2, the lower ends of these locking members terminate immediately above the roll stick 23. The roll stick is thus held in position during the time when the paper roll is in position on the standard and paper is being removed therefrom for wrapping purposes, and the like. The locks 25 are held on the studs 26 by means of cotter pins 21, 21, so that the locking members 25 are free to rotate in a complete circle about the studs 26. They will not slip off, but may be removed from the studs by the removal of the cotter pins 21, for the purpose of replacing them should they break or for any other purpose desired.

The rear ends of the arms adjacent the openings have slight extensions 28, 28 formed thereon, with seat portions 29, 29 formed on these extensions. These seat portions extend approximately at right angles to the direction of the arms 19 so that when the knife 18 is lifted to a position where the arms extend substantially horizontal, the seats also extend in substantially a horizontal direction and the latch members 25 can be lifted up and placed in position against the seats 29 and the knife allowed to rest by its own weight upon the latch members, thereby holding the knife out of the path of the roll of paper 24 as it is being mounted upon the cutter, particularly as shown in Figure 3. In this manner the knife is held completely out of the way of the operator when a roll of paper is being placed on the standard.

After the paper has been placed in position, the operator by slightly lifting the outer edge of the knife frees the locks 25 so that they can be turned into a downward position and come to the position shown in Figure 2 in the drawing, immediately above the ends of the roll stick 23, which holds it securely in position upon the saddles until the lock members are turned to one side sufficiently so that the roll stick can be lifted out of the saddles 22. It will be understood that the roll stick 23 projects slightly above the ends of the usual paper roll and that the projecting lower ends of the lock members 25 are approximately flush with the inner edges of the saddles 22, so that the paper roll is free to turn on the saddles 22 without any interference from the locking members 25, 25.

In operation the device is exceedingly simple in that when it is desired to place a roll of paper, usually wrapping paper and the like, upon the cutter, the knife is lifted to the position shown in Figure 3. The locking members 25 are turned to a vertical position so that the seat portions of the knife rest upon the ends of the locking members 25, thereby holding the knife out of the path of the roll of paper as it is placed upon the cutter. The empty roll stick is removed from the cutter and a new roll of paper placed thereon, with the roll stick in the saddles as shown in the drawing. Thereupon the operator lifts the knife slightly and turns the locks into a downward position so that the ends overlap the ends of the roll

stick. The knife is dropped so that the cutting edge thereof rests against the outer surface of the roll of paper in position for use. The locks are left in this position during the removal of paper from the roll, which in common practice is done by grasping the free edge of the paper and pulling upon it, thereby unrolling the paper until a sufficient length has been secured. The paper is then pulled sideways and cut by the edge of the knife 18 and detached from the roll.

In pulling on the roll of paper by the free edge, the operator oftentimes in a hurry will pull the paper quickly or give it a decided jerk, which sometimes causes the roll to be pulled out of the saddles and roll from the paper cutter, sometimes onto the operator in such manner that great inconvenience is caused and also injury has resulted from this source. Through the use of my device the paper stick is held in position until the paper is entirely removed from the roll stick.

With present devices because of the inability of the operator to keep the roll stick in position in the saddles when the roll of paper is quite reduced in size, it is common practice to remove 25 from the standards the small roll of paper remaining and to throw it away, resulting in a loss of paper. This amounts sometimes to as much as ten percent of the whole roll, so that in addition to providing a factor of safety through the use of 30 my improved device, a saving of paper is also effected.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

40 I claim:

1. A paper cutter comprising, in combination, a pair of standards having oppositely disposed roll stick saddles thereon, means whereby the said standards are held in spaced relation with each other, a knife pivotally mounted on said standards having a seat portion at its base, and a lock member pivotally mounted on one of said standards adapted to normally be positioned immediately above the open side of one of the saddles 45 to hold the roll stick therein and to be moved into engagement with the seat portion of said knife.

2. A paper cutter comprising, in combination, a pair of standards having roll stick saddles thereon, means whereby the standards are held in spaced relation with each other, a knife pivotally mounted at its base on said standards, and a lock member pivotally mounted on one of said standards having its lower end positioned immediately above the open side of one of the said saddles to hold the roll stick therein and adapted when 50 swung upwardly to engage the said knife whereby the knife is held out of the path of a roll of paper being inserted in said cutter.

3. A paper cutter comprising, in combination, 65 a pair of standards having roll stick saddles thereon, means whereby the standards are held in spaced relation with each other, a knife pivotally mounted at its base on said standards, and a lock member pivotally mounted on one of said standards and having its lower end normally positioned immediately above the open side of the saddle and below the knife mounting point, whereby the roll stick is held in said saddles and adapted to be swung away from the saddle to engage 70 the said knife whereby the knife is held 75

out of the path of a roll of paper being inserted in said cutter.

4. A paper cutter comprising, in combination, a pair of standards having roll stick saddles thereon, means whereby the standards are held in spaced relation with each other, a knife pivotally mounted at its base on said standards, and a lock member pivotally mounted on one of said standards approximately half way between the saddle and the point at which the knife is secured to the said standard and having its lower end positioned above one of the said saddles to hold the roll stick therein and adapted to engage the said knife when swung upwardly away from the saddle whereby the knife is held out of the path of a roll of paper being inserted in said cutter.

5. A paper cutter comprising, in combination, a pair of standards having roll stick saddles thereon and having inwardly projecting studs thereon, means whereby the standards are held in spaced relation with each other, a knife mounted on said cutter, and a locking member having an arcuate convex free end, said locking member being pivotally mounted on one of said studs and free to oscillate thereon, with its free end normally positioned by gravity above and adjacent the open side of one of said saddles whereby the roll stick is held in position in said saddle.

6. A paper cutter comprising, in combination, a pair of standards having roll stick saddles thereon, means whereby the standards are held in spaced relation with each other, a knife mounted on said standards, the knife having bases and having seat portions formed in said bases, and locking members on said standards adapted to engage the seat portions formed in the bases of said knife and hold the said knife out of the path of a roll of paper being placed on the said standards, and also to swing freely over the open side of the said saddles to hold the roll stick therein.

7. A paper cutter comprising, in combination, a pair of standards having roll stick saddles thereon and having studs projecting from the sides thereof in an inward direction, means whereby the said standards are held in spaced relation with each other, a paper knife pivotally mounted on the said standards having seat por-

tions formed at the base thereof, and locking members mounted on the said studs and free to oscillate thereon having their free ends normally positioned adjacent to the open sides of the said saddles to hold the roll stick therein and capable of being turned in the opposite direction whereby to engage the seat portions of the knife, thereby holding the said knife out of the path of a roll of paper being placed in the said cutter.

8. A paper cutter comprising, in combination, a pair of standards having roll stick saddles thereon and having studs projecting from the sides thereof in an inward direction, means whereby the said standards are held in spaced relation with each other, a paper knife pivotally mounted on the said standards having seat portions formed at the base thereof, the said studs being spaced intermediate the said saddles and the mounting point of the said knife, and locking members mounted on the said studs having their free ends normally positioned over the open sides of the said saddles to hold the roll stick therein and capable of being turned in the opposite direction whereby to engage the seat portions of the knife, thereby holding the said knife out of the path of a roll of paper being placed in the said cutter.

9. A paper cutter comprising, in combination, a pair of standards having roll stick saddles thereon and having studs projecting from the sides thereof in an inward direction, means whereby the said standards are held in spaced relation with each other, a paper knife pivotally mounted on the said standards having seat portions formed at the base thereof, the said studs being spaced at the half way point on the said standards between the open side of the said saddles and the mounting point of the said knife, and locking members mounted on the said studs having their free ends normally positioned over the open sides of the said saddles to hold the roll stick therein and capable of being turned in the opposite direction whereby to engage the seat portions of the knife, thereby holding the said knife out of the path of a roll of paper being placed in the said cutter.

ORVILLE O. SHELINE.
